(57) **CLAIM**

The ornamental design for a pattern for glass, as shown and described.

DESCRIPTION

FIG. 1 is a perspective view of an embodiment of a pattern for glass according to my new design;

FIG. 2 is an enlarged perspective view of a portion thereof;

FIG. 3 is a top plan view thereof;

FIG. 4 is an enlarged top plan view of a portion thereof;

FIG. 5 is a rear plan view thereof;

FIG. 6 is a front elevation view thereof, the rear elevation view being a mirror image thereof;

FIG. 7 is a right side elevation view thereof, the left side elevation view being a mirror image thereof;

FIG. 8 is an enlarged cross-section view thereof taken along line 8—8;

FIG. 9 is a perspective view of another embodiment of a pattern for glass according to my new design;

FIG. 10 is an enlarged perspective view of a portion thereof;

FIG. 11 is a top plan view thereof;

FIG. 12 is an enlarged top plan view of a portion thereof;

FIG. 13 is a rear plan view thereof;

FIG. 14 is a front elevation view thereof, the rear elevation view being a mirror image thereof;

FIG. 15 is a right side elevation view thereof, the left side elevation view being a mirror image thereof; and,

FIG. 16 is an enlarged cross-section view thereof taken along line 16—16.

The broken lines immediately adjacent the shaded areas represent the bounds of the claim, and all other broken lines are included for the purpose of illustrating portions of the pattern for glass that form no part of the claimed design. None of the broken lines form a part of the claimed design.
